UNITED STATES PATENT OFFICE.

DOUGALD McEACHERN, OF ERIE, CANADA.

DESIGN FOR A SAW-BLADE.

SPECIFICATION forming part of Design No. 31,308, dated August 1, 1899.

Application filed July 3, 1899. Serial No. 722,762. Term of patent 14 years.

To all whom it may concern:

Be it known that I, DOUGALD McEACHERN, a citizen of the United States, residing at Erie, British Columbia, Canada, have invented and produced a new and original Design for Saw-Blades, of which the following is a specification, reference being had to the accompanying drawings, forming part thereof, and in which—

Figure 1 is a side view of a saw-blade, showing my new design. Fig. 2 is an edge view thereof, and Fig. 3 is a detail side view of one of the teeth embodying my design.

The leading or material feature of my design consists in the design of the tooth forming the subject-matter of the accompanying illustrations.

In the illustrations the teeth have their front and rear edges A and B sloped rearwardly toward their inner ends, while the outer or lower edges of the teeth are formed with cut-away portions or notches C, whose front walls or edges meet the front edges of the teeth at the extreme forward lower corners of the teeth at an acute angle, producing a sharp keen point at such edge and narrow toe-like portions D at the front edges of the teeth. The

rear edge wall E of the notch C extends from the inner end of the front wall E' downwardly to the base of the tooth on a line almost at right angles to that of the base edge of the tooth, meeting such base edge at a point at or slightly in rear of a point midway between the front and rear edges of the tooth. The tooth thus designed simulates the appearance of a boot, the resemblance being enhanced by the slope of the tooth and the forwardly and rearwardly curving lines which connect each tooth with those in front and rear thereof.

The alternate teeth are tapered at F on their opposite sides, so that each tooth presents in edge view, as seen in Fig. 2, a tapered appearance, narrowing gradually on one side toward its rear end.

Having thus described my invention, what I claim as new, and desire to secure by Letters Patent, is—

The design for a saw-blade, as herein shown and described.

DOUGALD McEACHERN.
